UNITED STATES PATENT OFFICE.

ARTHUR STOCKSTROM, OF ST. LOUIS, MISSOURI, ASSIGNOR TO AMERICAN STOVE COMPANY, OF ST. LOUIS, MISSOURI, A CORPORATION OF NEW JERSEY.

DESIGN FOR AN OIL-STOVE CHIMNEY.

54,699.

Specification for Design.

Patented Mar. 9, 1920.

Application filed September 3, 1919. Serial No. 321,478. Term of patent 14 years.

To all whom it may concern:

Be it known that I, ARTHUR STOCKSTROM, a citizen of the United States, residing at St. Louis, in the State of Missouri, have invented a new, original, and ornamental Design for Oil-Stove Chimneys, of which the following is a specification, reference being had therein to the accompanying drawings.

In the accompanying drawing—

Figure 1 is a side elevation of an oil stove chimney showing my new design.

Fig. 2 is a top plan view of Fig. 1.

I claim—

The ornamental design for an oil stove chimney, as shown.

In testimony whereof, I hereunto affix my signature.

ARTHUR STOCKSTROM.
